UNITED STATES PATENT OFFICE.

CARL JOHN NELSON, OF BERKLEY, MICHIGAN.

GUARD FOR SHAPER HEADS.

Application filed February 20, 1928. Serial No. 255,542.

This invention relates to guards for enclosing vertical wood shapers, which rotate at very high speeds, to prevent injury to the operators, and thereby not only to protect 5 the operators but to relieve them of the severe mental tension which reduces their efficiency to such an extent that their output falls off seriously during the later hours of the working day. The constant danger from 10 unprotected cutting tools of this character is so great that the operators involuntarily slow down because of mental strain long before physical fatigue sets in, as has been demonstrated by comparisons of results obtained 15 with the same machines before and after my guards for the shaper heads were installed.

This invention consists of a guard shell which normally encloses the shaper-head and 20 the knives mounted thereon until the work is moved toward it and then rises to uncover the shaper knives to a predetermined extent to permit the operator to press the work against the cutters, the guard coming down 25 to protective position as soon as the work is moved away from the cutters, in combination with pneumatic means for actuating the guard and a pneumatic valve which is actuated by the work and which controls the 30 operation of the guard.

It further consists of the details of construction illustrated in the accompanying drawings and particularly pointed out in the claims.

In the accompanying drawings, Fig. 1, 35 is a plan of a wood shaper equipped with my novel guard. Fig. 2, is an elevation of this guard, the shaper head being shown in dotted lines. Fig. 3, is a section on the line 40 3—3 of Fig. 2. Fig. 4, is a vertical section of the actuating mechanism for the guard. Fig. 5, is a vertical section of the control valve.

Similar reference characters refer to like 45 parts throughout the several views.

The well known cutter head 1 shown in plan in Fig. 1 is usually rectangular in cross-section and to it are attached the knives 2, the head being mounted on a shaft 3 which 50 projects upwardly from the table 4. The upper end of the shaft is journaled in a bracket 5 carried by a post 6 which projects upward from a base 7 secured to the table 4. As these heads rotate as high as eight to ten 55 thousand rotations per minute, the danger

to the hands and arms of the operators is apparent, especially where work is duplicated to such an extent that the operations become mechanical.

In my novel construction, a hub 10 is attached to the base 7 and a round vertical post 11 is mounted in this hub. The upper end 12 of the post is reduced in diameter and on the lower end is slidable a head 13 carrying a key 14 slidable in a key-way 15 shown by a dotted line in Fig. 4, and this key is positioned by the pins 16 and screw 17. A second head 18 is slidable on the upper end of the post and is provided with a stuffing box 19. A cylinder 21 is held between the heads by means of four bolts 20. The lower head is provided with a vent passage 23 to prevent air being compressed in the lower end of the cylinder.

A piston is mounted on the post and consists of two disks 24 pressed toward each other by a nut 25 and a packing ring 26 is held between the beveled edges of the disks and pressed against the interior wall of the cylinder. Air under pressure is conducted 75 to the longitudinal bore 27 of the post by a pipe 28 and flows into the space above the piston through passages 29 above the piston and raises the cylinder and the heads. This movement is limited by an adjustable clamp 80 85 30 shown in Figure 3.

The heads are preferably square in plan and the shell 33 is secured to these heads by screws 36, being formed of two parallel sides 32 and a semi-cylindrical end 34. A reinforcing strap 35 and two short plates 37 may be used, if desired. The guard is elevated by air pressure but descends by its own weight, the fall being cushioned by a rubber collar 38. The movements of the guard are 90 95 controlled by the valve shown in Fig. 5.

A valve body 40 is provided with a cylindrical lining 41, held in position by means of the collars 42 and 43. The pipe 44 connects to a source of air under pressure while 100 the pipe 28 connects to the guard. A cylindrical valve 45 has a circumferential groove 51 which connects the ports 46 and 46 when the valve is depressed by work sliding on the table 4 coming in contact with the rounded 105 knob 48 which is adjustably mounted on the valve. The lower end of the valve is formed with a central bore 52 which receives a spring 49 and with an exhaust port 50 which connects to this central bore. The lower col- 110

lar 43 has an exhaust opening 53 to permit air passing from the pipe 28 through the port 50 and bore 52 to escape to the atmosphere.

- 5 The parts are normally in the position shown in the drawings. When work is slid on the table toward the shaper head, it passes over the button 48 and depresses it against the pressure of the light spring 49.
- 10 Air rushes from the pipe 44 through port 46, grove 51, second port 46, pipe 28, passage 27 in post 11 and passages 29 into the space between the piston 24 and head 18 and forces the guard up until it is stopped by 15 the clamp 30. When the work is finished, it is moved back from over the button 48 which permits the spring 49 to raise the valve. The air in the cylinder now escapes through the passages 29 and 27, pipe 28, 20 ports 46 and 50, bore 52 and opening 53 to the atmosphere, permitting the guard to slide down over the shaper head. The movements of the guard are very rapid so that the shaper head is enclosed at all times 25 when not in use. The position of the button 48 relative to the shaper head will be determined by the character of the work.

The details of construction and the proportion of the parts may all be changed by 30 those skilled in the art without departing from the spirit of my invention as set forth in the following claims.

I claim:

1. A guard for a shaper head comprising 35 a vertically movable shell adapted to enclose said head, a vertical post having a longitudinal passage, a cylinder, heads at the ends of the cylinder slidable on the post, a piston for the cylinder secured to the post, 40 a valve adapted to be positioned by the work presented to the cutter head, a pipe connecting the valve to a source of air under pressure and a pipe connecting the valve to the passage in said post.
- 45 2. A guard for a shaper head comprising a vertically movable shell adapted to enclose said head, a cylinder attached to the shell, a piston within the cylinder, a hollow piston rod and a pipe connecting thereto to permit

air to pass into and out of the cylinder to 50 cause it to move up, a valve body adjacent the cutter head having a vertical bore and two ports, a pipe connecting to a source of air under pressure and to one of said ports, the other port connecting to said piston rod 55 by said first named pipe, a valve slidable within said valve body and provided with a transverse passage which connects said ports when depressed and with an exhaust passage which connects to the second named 60 port when said valve is elevated, a spring to elevate the valve, and a button attached to the upper end of the valve and adapted to be depressed by work being presented to the shaper head.

3. A guard for a shaper head comprising a vertically movable shell having parallel sides and a semi-cylindrical end adapted to enclose said head, a vertical post having a longitudinal bore, a cylinder, rectangular 70 heads at the ends of the cylinder slidable on said post to which heads the parallel sides of the shell are attached, a piston for said cylinder attached to said post whose bore terminates above said piston, and a valve to 75 control the flow of air under pressure to the bore of said post.

4. A guard for a shaper head comprising a stationary part and a vertically movable part, said parts embodying an air cylinder 80 and a piston therein, means to conduct air to and from said cylinder, a valve body adjacent the shaper head, a piston valve therein, pipes connecting said valve body to the guard and to a source of air under pressure, and means in the path of the work to move said valve.

5. A guard for a shaper head comprising a stationary part and a vertically movable part, said parts embodying a cylinder and 90 a piston therein, means to conduct fluid under pressure to and from said cylinder, a valve mechanism adjacent the shaper head, pipes connecting said valve mechanism to the guard and to a source of fluid under 95 pressure, and means in the path of the work to operate the valve mechanism.

CARL JOHN NELSON.
